UNITED STATES PATENT OFFICE.

ABEL P. HOLCOMB AND AUGUST HEINE, OF SILVER CREEK, NEW YORK.

CENTRIFUGAL FLOUR-BOLT.

SPECIFICATION forming part of Letters Patent No. 271,846, dated February 6, 1883.

Application filed November 4, 1882. (No model.)

To all whom it may concern:

Be it known that we, ABEL P. HOLCOMB and AUGUST HEINE, of Silver Creek, in the county of Chautauqua and State of New York, have invented new and useful Improvements in Centrifugal Flour-Bolts, of which the following is a specification.

This invention relates to certain improvements in that class of bolting-machines generally known as "centrifugal bolts," which are provided with a rotating cylinder and rotating beaters arranged within the cylinder, whereby the material to be bolted is driven against all parts of the cylindrical bolting-surface.

Our invention has the object to improve the operation of this class of machines by properly disintegrating and separating the material before it reaches the bolting-surface by excluding the air as much as possible from the interior of the bolting-cylinder, and in other particulars; and our invention consists of the improvements which are hereinafter more fully described, and pointed out in the claims.

In the accompanying drawings, consisting of three sheets, Figure 1 is a longitudinal sectional elevation of our improved bolting-machine. Fig. 2 is an elevation of the front end of the machine, with the feed mechanism in section. Fig. 3 is an elevation of the rear end of the machine. Fig. 4 is a cross-section of the machine, looking rearward. Fig. 5 is a cross-section in line xx , Fig. 1. Fig. 6 is an enlarged longitudinal section of the feed end of the bolting-cylinder. Fig. 7 is a cross-section in line yy , Fig. 1. Fig. 8 is a front elevation of the disintegrating-head arranged within the bolting-cylinder. Fig. 9 is an elevation of the bolting-cylinder, illustrating the means by which the bolting-cloth is secured thereto. Fig. 10 is a longitudinal section thereof on an enlarged scale. Fig. 11 is a longitudinal section of the outer end of the clothing. Fig. 12 is a similar view, illustrating the means whereby the sections of the clothing are secured together.

Like letters of reference refer to like parts in the several figures.

A represents the frame of the machine, and A' the inclosing casing, which is made air-tight as nearly as practicable.

B represents the bolting-cylinder, which is composed of two heads, D D', connected by stay bolts, rods, or bars d, and which is covered with bolting-cloth b of suitable mesh, supported by suitable rings, d'. The head D of the feed end of the bolting-cylinder is provided with a hollow journal, e, which turns in a bearing, e', secured to the frame A, and the head D', at the tail end of the bolting-cylinder, is provided with a similar hollow journal, e'', which turns in a bearing, e''.

f represents the rotating beaters, which are arranged in the bolting-cylinder and secured to rings f'. The latter are attached by arms f² to a shaft, f³, which passes through the hollow journals e e'', and is supported in bearings f⁴ f⁵. The cylinder B is slightly inclined from the head D toward the head D' to cause the material to pass slowly through the cylinder, or the beaters f may be arranged spirally to propel the material through the cylinder in the proper direction, or both means may be employed together to impart the necessary movement to the material.

g represents a rotating spiral brush, which is arranged transversely at the head of the machine, and g' is the trough in which the brush rotates, and which is constructed of wire-cloth or perforated metal having openings which permit the passage of the material to be bolted, but retain all larger impurities—such as dough-balls, nails, stones, &c. The latter pass through an opening, g², at the end of the perforated trough, into a receptacle, G, which is provided with suitable slides, through which the accumulated material can be removed from time to time.

g³ represents the feed-spout, through which the material to be bolted is introduced into the trough g'.

i represents a screw-conveyer arranged underneath the perforated trough g', and i' is the trough of the conveyer i, which receives all the fine material which has passed through the openings of the perforated conveyer-trough g'. The conveyer i delivers the fine material to the feed-spout i². The spiral brush serves to disintegrate the material and forces the fine particles through the perforations of the trough g' into the trough i' below. The feed-

spout i^2 discharges the material into a conical hood, J , which is secured with its large end to the outer side of the head D , so as to turn with the cylinder B , and which turns with its small end on a fixed collar or short sleeve, j , which is secured to the adjacent portion of the casing A' . The hood J is fitted so snugly on the collar j that but little air can leak into the cylinder B through this joint; and, if desired, this joint may be further protected by a ring of india-rubber or leather.

The head D is composed of an annular plate, k , having a marginal flange, k' , to which the ticking of the bolting-cloth is secured.

This plate k is provided with a central circular opening, k^2 . On the outer side of the plate k are formed radial ribs or arms k^3 , which have their outer ends beveled to fit against the inner side of the head J , and which extend inwardly across the central opening, k^2 , to a curved or conical deflector, L , which surrounds the inner end of the journal e and projects with its small end into the opening k^2 . The plate k , ribs k^3 , deflector L , and journal e are preferably cast in one piece. The deflector L does not extend to the hood J , so that an annular opening, l , is formed between the edge of the deflector and the hood. The material delivered into the hood J by the spout i^2 slides through the annular opening l , against the outer side of the plate k , and is picked up by the ribs k^3 , and elevated by the same until the ribs in rotating assume an inclination which causes the material resting on the same to slide off, when the material strikes against the inner side of the deflector L , and is thereby deflected through the central opening, k^2 , into the bolting-cylinder B .

l is a disk or circular plate secured to the shaft f^3 , near the inner side of the opening k^2 , and provided with one or more circular rows of pins or beaters, l^2 , arranged opposite the edge of the feed-opening k^2 . The material entering the bolting-reel through the opening k^2 strikes against the rotating disk l near its center, and is driven outwardly by the centrifugal force between the rotating pins l^2 , which disintegrate the material and distribute the same in a spray over the inner surface of the surrounding portion of the bolting-cylinder. In passing through the cylinder B from the head D to the head D' the material is thrown by the beaters l against the bolting-cloth of the cylinder B and thereby separated, the flour passing through the meshes of the bolting-cloth into the surrounding inclosed space, while the lighter particles remain in the bolting-cylinder and finally arrive at the head D' . The latter is provided on its inner side with radial ribs m and with a central discharge-opening, m' , which is surrounded by a short collar, m^2 , extending rearwardly.

m^3 is a curved or conical deflector, having its convex side turned rearwardly and connected with the inner ends of the ribs m and the inner end of the journal e^2 . The material which

reaches the inner side of the head D' is lifted by the ribs m until the increasing inclination of the ribs causes the material to slide off, when it strikes the convex side of the deflector m^3 , and is thereby deflected rearwardly and discharged through the opening m' into a receptacle, M . The latter is arranged between the head D' and the rear wall of the casing A' , and projects with its lower end through said casing. This receptacle is provided with two automatic discharge-valves, $n\ n'$, which prevent the entrance of the external air, and which open at different times under the pressure of the accumulated material and permit the discharge of the material without admitting air to the cylinder B . The action of the beaters expels the air through the meshes of the bolting-cloth, and tends to draw air inward through the central discharge-opening and the receptacle M , communicating therewith. This is prevented by the automatic valve or valves, which are kept closed by the air-pressure until the weight of the accumulated material preponderates, when the valve next the material opens and discharges the same, but immediately closes again. It is very important to avoid the admission of air to the cylinder, as the presence of air-currents interferes with the operation of bolting, and it is especially important to avoid the admission of air at the tail end of the cylinder, because ingoing currents of air would carry back into the cylinder the light floating bran-specks, which would result in rendering the flour specky.

O represents an opening formed in the head-board of the casing A' , within the collar j , for the purpose of admitting air to the head of the bolt, when required. The opening O is provided with a slide, o' , whereby it may be entirely closed, if desired, or its size may be regulated and the ingoing air-currents controlled. By admitting air at the head of the bolt the air passes through the bolt from the head toward the tail, and the return of the specks from the tail portion of the bolt toward the head is thereby prevented.

PP' represent two screw-conveyers, arranged below the bolting-cylinder B , one above the other, and provided in their troughs with a suitable number of openings controlled by slides p , so that the bolted material can be drawn off at any desired point.

q represents the driving-pulley secured to the end of the shaft f^3 , and q' is an endless belt, which runs around a small pulley, q^2 , on the shaft f^3 , and a larger pulley, q^3 , on the shaft of the lower conveyer, P' , whereby the latter is rotated.

r represents an endless belt, which runs around a small pulley, r' , on the shaft of the lower conveyer, P' , and a larger pulley, r^2 , on the hollow journal e^2 , whereby the cylinder B is rotated from the conveyer P' with much less speed than the beaters. The upper conveyer, P , is driven from the lower conveyer, P' , by gear-wheels $s\ s'$, and the conveyer i is driven

from the conveyer P by means of a counter-shaft, s^2 , and an endless belt, s^3 . The spiral brush G is driven from the conveyer i by gear-wheels s^4 s^5 .

5 T T' represent adjustable transverse partitions, arranged in the hopper or lower portion of the casing above the conveyer P for the purpose of more perfectly separating the different grades of material which are bolted through the bolting-cloth. These partitions are provided with rods t t' , which extend through one of the end walls of the casing, and whereby the partition can be adjusted. The partitions T T' prevent the material which 15 has passed through the bolting-cloth from being distributed over the entire length of the casing by the air-currents which are generated by the beaters, but they confine the different grades of material to those portions of the casing in which each grade should be collected and to those portions of the conveyer from which each grade should be drawn off. U represents a blast-fan, which is actuated by a belt, u, from the beater-shaft f^3 .

25 w' represents the blast-pipe of the fan, arranged parallel with the side of the cylinder B, in close proximity therewith, and provided on the side adjacent to the cylinder with perforations, whereby the air which is driven into 30 the pipe by the blast-fan is delivered in jets upon the surface of the bolting-cylinder, whereby the meshes of the latter are freed from any material which may tend to adhere to the same. The distance between the cylindrical surface 35 of the bolt and the perforated air-pipe remains the same during the revolutions of the bolt, and the air-blast operates, therefore, uniformly upon all parts of the bolting-cloth.

The bolting-cloth is applied to the bolting-40 cylinder in two cylindrical sections, which may each be composed, if desired, of one or two or more different grades of cloth.

45 v represent strips of ticking or other strong cloth, secured to the outer ends of both sections of the bolting-cloth, and v' v'' are strips of ticking secured to the inner ends of the bolting-cloth sections. The strips v' v'' are provided with projecting hooks v^2 , which are secured to the strips by eyelets or rivets, as 50 represented in Fig. 12, and the outer strips, v , are provided along their outer edges with cords v^3 , which are sewed into the strips along their outer edges, so as to form a projecting rim on said strips.

55 v^4 represents tapering rings or hoops, which are applied to the outer sides of the outer strips, v , in such manner that the corded rims of said strips bear against the outer edges of the tapering hoops. The latter conform in 60 their shape to the tapering flanges k' , and clamp the outer strips of ticking, v , against said

flanges. The adjacent inner strips, v' , are drawn together by a cord, v^5 , which is laced around the hooks v^2 , secured to said strips, as clearly shown in Fig. 9. The tension applied 65 to the bolting-cloth in this manner clamps the outer strips, v , firmly between the tapering flanges k' and tapering hoops v^4 , and at the same time stretches the bolting-cloth and equalizes the strain upon both sections of the 70 bolting-cloth. The clothing of the reel is in this manner easily applied, stretched, and, if necessary, as easily removed.

We do not in this application desire to cover any improvements herein shown except those 75 which are specifically pointed out in the claims, and reserve the right to cover such other improvements by separate applications for patent.

We claim as our invention—

1. The combination, with a rotating bolt and rotating beaters f , of a feed device composed of a head, D, having a central opening, k^2 , ribs k^3 , a deflector, L, and a hood, J, substantially as set forth.

2. The combination, with a revolving bolt and revolving beaters, of means whereby the residue is discharged at the tail end of the bolt near the axis thereof, and a receptacle which receives the residue, and is provided with one 90 or more automatic valves, which exclude the air from the bolt, substantially as set forth.

3. The combination, with a revolving bolt, revolving beaters, and an inclosing-case formed with an air-inlet opening at the head of the 95 bolt, of a residue-discharge and one or more automatic valves, which exclude the air from the tail end of the bolt, substantially as set forth.

4. The combination, in a flour-bolt, with a 100 head having a tapering marginal flange, k' , and a detachable tapering hoop, v^4 , surrounding said flange, of the bolting-cloth and a strip to which the bolting-cloth is attached, and which is arranged between the flange k' and 105 the hoop v^4 , and provided with a raised outer edge, v^3 , which bears against the tapering hoop, substantially as set forth.

5. The combination, with a flour-bolt, of two heads arranged near the extremities of the 110 bolt and provided with tapering flanges k' , tapering hoops v^4 , and two sections of bolting-cloth, provided at their outer ends with strips v , having raised outer edges, and at their inner ends with strips v' , having projecting hooks 115 v^2 , and a cord, v^5 , whereby the inner strips are laced together, substantially as set forth.

ABEL P. HOLCOMB.

AUG. HEINE.
